CLAIM

The ornamental design for a fitted top bedsheets, as shown and described.

DESCRIPTION

FIG. 1 is a perspective view of a fitted top bedsheets showing my new design;

FIG. 2 is a top view of the fitted top bedsheets;

FIG. 3 is a right side view of the fitted top bedsheets;

FIG. 4 is a left side view of the fitted top bedsheets;

FIG. 5 is a rear view of the fitted top bedsheets;

FIG. 6 is a front view of the fitted top bedsheets; and

FIG. 7 is a bottom view of the fitted top bedsheets;

FIG. 8 is a perspective view of a second embodiment of the fitted top bedsheets;

FIG. 9 is a top view of the second embodiment of the fitted top bedsheets;

FIG. 10 is a right side view of the second embodiment of the fitted top bedsheets;

FIG. 11 is a left side view of the second embodiment of the fitted top bedsheets;

FIG. 12 is a rear view of the second embodiment of the fitted top bedsheets;

FIG. 13 is a front view of the second embodiment of the fitted top bedsheets; and

FIG. 14 is a bottom view of the second embodiment of the fitted top bedsheets;

FIG. 15 is a perspective view of a third embodiment of the fitted top bedsheets;

FIG. 16 is a top view of the third embodiment of the fitted top bedsheets;

FIG. 17 is a right side view of the third embodiment of the fitted top bedsheets;

FIG. 18 is a left side view of the third embodiment of the fitted top bedsheets;

FIG. 19 is a rear view of the third embodiment of the fitted top bedsheets;

FIG. 20 is a front view of the third embodiment of the fitted top bedsheets; and

FIG. 21 is a bottom view of the third embodiment of the fitted top bedsheets.
